UNITED STATES PATENT OFFICE.

WALTER VAN B. ROBERTS, OF PRINCETON, NEW JERSEY, ASSIGNOR TO ROBERT E. HOPKINS, OF TARRYTOWN, NEW YORK.

VIBRATOR.

1,243,628.

Specification of Letters Patent. Patented Oct. 16, 1917.

Application filed June 2, 1916. Serial No. 101,427.

To all whom it may concern:

Be it known that I, WALTER VAN B. ROBERTS, a citizen of the United States, residing at Princeton, in the county of Mercer and State of New Jersey, have invented certain new and useful Improvements in Vibrators; and I do hereby declare the following to be a full, clear, and exact description of the invention, such as will enable others skilled in the art to which it appertains to make and use the same.

This invention relates to vibrators for use in foundries and the like.

It has for an object to provide a very simple construction in which the operative parts are effectively protected against mechanical injury and also to protect the user from electrical currents.

A further object of this invention is the provision of a housing formed of complementary sections, of which one section is of non-magnetic metal while the other one may be of magnetic material to assist the electro-magnets in said housing, and movably carried in said non-magnetic portion is an armature to be affected by magnetic impulses from windings in said housing.

Further objects will be apparent from the following specification, appended claims and drawings, in which.

Figure 1 is a side elevation of the vibrator,

Fig. 2 is a plan view thereof,

Fig. 3 is a bottom view of the upper portion of the housing or casing,

Fig. 4 is a vertical sectional view through the vibrator as on the line 4—4 of Fig. 2, and

Fig. 5 is a vertical cross sectional view as on the line 5—5 of Fig. 2.

This vibrator is intended for use in foundries and it is apparent that it may be used in several capacities such as removing the patterns from the mold or for dislodging powder subsequently applied to the mold if desired.

Referring to the drawings, in which the several parts are described, 10 indicates a base which will preferably be of magnetic metal and this base may be cast to have the ears 11 formed thereon, which may be perforated as at 12 to receive fastening means, and to the sides of this base member are formed lugs 13 which receive fastening means for an upper member of said casing.

The base member has a flange 14 formed thereabout, upon which the lower face of an upper member 15 bears. The upper member may be cast of a non-magnetic metal such as aluminum and will preferably have the tapering sides as shown, to permit the casting being drawn from the mold. The side walls of the member 15 have the lugs 16 formed thereon to receive screws 17 which pass through the lugs 13 and the upper member 15 has a boss 17' formed thereon which is drilled as at 18 to receive the stem 19, on which an adjusting nut 20 may be placed to regulate the compression of a spring 21 which serves to raise the stem 19 and the armature 22 carried thereby, from contact with the cores of the electro-magnets including the windings 24. The casing 15 has wings 25 formed therein, which serve as guides for the armature 22 to restrict said armature to movement in a vertical position with respect to the casing 15. The stem 19 may be secured to this armature in any desired means, but I have shown a threaded portion 26 on said stem which engages in a threaded socket 27 in said armature.

The cores 23 have their lower ends tapped as at 28 to receive the screws 29 which pass through the base member 10 as shown, and the windings 24 are connected to the electric conductors 30 so that as a pulsating current is sent through said conductors and the windings 24, the armature 22 is vibrated and in its vibration the entire vibrator is agitated, so that a vibrating motion is imparted to a bench or flask to which the vibrator may be applied.

The vibrator above described is designed for operation with alternating current included within the housing, but when it is desired to operate the vibrator on direct current such as a lighting circuit, I provide an interrupter 31 which may be of any preferred construction to make and break a circuit through the windings 24 and the form of interrupter shown, comprises a winding 32 which supports the magnetic heads 33 and 34 which, as said winding is energized, attract an armature 35 to which one of the contacts of the interrupter 31 is attached. A spring 36 serves to return the armature and a screw 37, which may be adjustably secured in a bracket 38, supports the other of the contacts of the interrupter 31.

31. The winding 32 also adds a load to the circuit which relieves to a slight extent, undue heating of the coils 24 for use with direct current as the winding 32 partly forms a resistance coil, but it is understood that for use with alternating current such as from a lighting circuit, no other interrupter is required as the frequency of said alternating current establishes the vibration 10 from the armature 22.

It is apparent that modifications may be made within the scope of the appended claims and the foregoing description, and that the drawing submitted herewith is for 15 illustrative purposes only.

Having thus described this invention, I claim:—

In a vibrator of the class described, a base of magnetic material having perforated 20 ears formed thereon, a flange rising from said base, lugs formed on the sides of said

base, a housing of non-magnetic material secured to said base, lugs formed on the sides of said housing, fastening means passing through the lugs on said base and said 25 housing, a boss formed on said housing, a stem slideable through said boss, an armature carried by said stem, an adjusting nut carried by said stem, a spring in compression between said boss and said adjusting 30 nut, wings formed in said housing to guide said armature in a vertical movement, and electro-magnets in said housing secured to said base, having the windings thereof in closed circuit with an external source of 35 pulsating current.

In testimony whereof I affix my signature in presence of two witnesses.

WALTER VAN B. ROBERTS.
